UNITED STATES PATENT OFFICE.

ALBERT FRENCH, OF EAST ROCKPORT, OHIO, ASSIGNOR OF ONE-HALF TO
ALFRED FRENCH, OF WASHINGTON, DISTRICT OF COLUMBIA.

THILL-COUPING.

SPECIFICATION forming part of Letters Patent No. 337,761, dated March 9, 1886.

Application filed September 12, 1885. Serial No. 176,877. (No mod. 1.)

To all whom it may concern:

Be it known that I, ALBERT FRENCH, a citizen of the United States, residing at East Rockport, in the county of Cuyahoga and State of Ohio, have invented certain new and useful 5 Improvements in Thill-Couplings; and I do hereby declare that the following is a full, clear, and exact description of the invention, which will enable others skilled in the art to 10 which it appertains to make and use the same.

My invention relates to thill-couplings, the object being to provide a device of this character whereby all lateral movement of the 15 thill-iron in the draw-iron and the consequent rattling are prevented.

A further object of the invention is to provide a thill-coupling possessing the above-mentioned advantage which may be manufactured at a comparatively slight cost, one 20 that will be strong and durable and not likely to get out of order.

My invention consists in the details of construction and combinations of parts herein- 25 after fully described and claimed.

In the drawings, Figure 1 is a perspective view of a thill-coupling embodying my invention. Fig. 2 is a longitudinal vertical section of the same. Fig. 3 is a transverse vertical section, and Fig. 4 is a detail view of the 30 bushing removed.

Corresponding parts in the several figures are denoted by the same letters of reference.

Referring to the drawings, A represents a 35 portion of the axle, secured to which is a clip, B, said clip having threaded ends. Fitting upon and connecting the ends of the clip is a bar or plate, C, and holding said plate in place are nuts a, which engage the threaded ends of 40 the clip.

D represents the draw-iron, which projects outwardly from the clip, and is preferably formed integral therewith. This draw-iron consists of two outwardly-extending ears, 45 each of which is provided with an opening, b.

E represents the thill-iron, which is adapted to be bolted or otherwise firmly secured to the thill. This thill-iron E is formed with a head, d, which has a transverse opening or 50 passage.

Within the opening or passage of the head d is formed a shoulder, f, which is preferably circumferential, and is located midway the ends of the head. This shoulder f may be formed by reaming out the head from opposite sides. 55

G represents a sectional bushing, which is preferably of elastic material, such as rubber or leather. The two parts or sections of the bushing G are passed through the openings in the ears of the draw-iron, and bear with their inner ends against the shoulder f, their outer ends resting in the openings of the ears of the draw-iron. 60

H represents a headed bolt, which passes 65 through the bushing or packing, and which is held in place to secure the parts together by a nut, g. The outer ends of the sections of the elastic bushing bear against the head of the bolt and the nut, and they serve as 70 cushions for the same to prevent their wear and rattling. It will be observed that as the ends of the sectional bushing bear against the sides of the shoulder the lateral movement of the thill-iron is prevented, and as the bushing fits tightly in the openings forward and 75 backward movement of the thill-iron is also prevented.

I am aware that it is not broadly new to provide the opening of a thill with a sectional 80 bushing having its outer ends located in the opening of the draw-iron and forming a bearing for the pivotal bolt its entire length; but in constructions of this class, so far as I am acquainted, conical openings have been provided in the draw and thill irons, and a conical sectional bushing employed in combination with a bolt made conical for half its length. This construction of coupling has never been brought into general use, owing to its expensive 85 construction, a special form of bolt being necessary, which, if lost, could only be replaced by the manufacturer. The bushings are not alike, one of them having a smooth interior bore, and the other a conical bore to fit the 90 conical portion of the bolt.

My construction differs from the construction before mentioned in that I make the openings of both the thill and draw irons plain, and provide a plain tubular bushing to fit in the 95 100

thill-iron and have its ends rest in the openings of the draw-iron and in combination with a plain or ordinary bolt, thereby greatly simplifying the construction and reducing the 5 cost of manufacture to the minimum.

Having thus described my invention, I claim—

The combination, with the draw and thill-irons having cylindrical openings, and an interior circumferential shoulder in the thill-iron, of a sectional cylindrical bushing having plain inner and outer surfaces, the inner ends

of said bushing bearing against opposite sides of the shoulder *f*, and their outer ends bearing in the openings of the draw-iron, and the bolt *A*, corresponding to and passing through the opening in the bushing and a nut, substantially as set forth.

In testimony whereof I affix my signature in presence of two witnesses.

ALBERT FRENCH.
